BY Ackley & Tolton
his ATTORNEYS.

UNITED STATES PATENT OFFICE.

BRONSON C. SKINNER, OF DUNEDIN, FLORIDA, ASSIGNOR TO SKINNER MACHINERY COMPANY, OF DUNEDIN, FLORIDA, A CORPORATION OF FLORIDA.

POLISHING MACHINE.

Application filed February 23, 1924. Serial No. 694,573.

To all whom it may concern:

Be it known that I, BRONSON C. SKINNER, a citizen of the United States, residing at Dunedin, in the county of Pinellas and State of Florida, have invented certain new and useful Improvements in Polishing Machines, of which the following is a specification.

The present invention relates to improvements in polishers, particularly that type of polisher designed for conveying, brushing and polishing of fruits in general, particularly oranges, apples, lemons, grapefruit and the like.

It is customary to employ an apparatus consisting of parallel spaced spiral conveying brushes all driven in the same direction, at the same speed, providing between adjacent brushes runways in which the fruit settles during the polishing and conveying operation. On an over supply of fruit being delivered to an apparatus of the above-mentioned type, the rotation of the brushes all in the same direction tends to crowd the fruit toward one side of the apparatus and to throw the same against the edge of the side rail or flare board, bruising the skin and permanently injuring the fruit, resulting in serious loss to the packer.

The present invention relates to an improvement in the spiral brush parallel spaced roll polisher, which will overcome the injuring and bruising of the fruit due to its being thrown against the side rail or flare board of an apparatus during its operation.

The invention consists essentially in providing adjacent that side of the apparatus toward which the brushes revolve a suitable buffer brush the periphery of which is raised in a plane above the horizontal plane of the regular conveying and polishing brushes, affording a buffing cushion and repellent for the fruit projected thereagainst; to provide a brush of the above-mentioned type rotated in the same direction as the regular conveying and polishing brushes and which due to its rotation deflects the fruit projected against the same in a direction toward the conveying and polishing brushes.

With the above-mentioned and other objects in view, the invention consists in the novel construction and combination of parts hereinafter described, illustrated in the accompanying drawings, and set forth in the claims hereto appended, it being understood that various changes in the form, proportion,

size and minor details of construction within the scope of the claims may be resorted to without departing from the spirit or sacrificing any of the advantages of the invention.

To more fully comprehend the invention, reference is directed to the accompanying drawings, wherein—

Fig. 1 is a view in top plan of the preferred embodiment of my apparatus, with the driving gear case covers removed.

Fig. 2 is a longitudinal sectional view.

Fig. 3 is a transverse sectional view on line 3—3, Fig. 2.

In the drawings wherein like characters of reference designate corresponding parts, 1 indicates a suitable open top frame carried on legs 2 and mounting at its ends transverse roller supports 3, one disposed in a plane slightly below the other. Each of the supports 3 mounts a plurality of bearings 4, corresponding bearings of each support being disposed with their bearing apertures in alignment. Rotatably mounted at opposite ends in respective end bearing supports 4, are the rollers 5 provided on their peripheral surface with spirally disposed brush surfaces 6 extending the full length thereof. The upper ends of rollers 5 each carry stub shafts 7 independently connected to a drive shaft 8 through beveled gear driving connections 9, each connection being mounted in a gear box 10. It will be observed that the rotation of the shaft 8 in the direction of the arrow, Fig. 2, will cause a simultaneous rotation of the rollers 5, all in the same direction as illustrated by the arrows in Figure 3.

Rotatably mounted at its ends in bearings to extend parallel with the roller 5 at the side of the apparatus toward which the rollers 5 rotate, is an auxiliary roller 11 disposed in a plane above the rollers 5 and mounting on its surface a brush consisting of annular rows of tufts 12. The roller 11 is rotated in a direction corresponding to that of rollers 5 through a pinion 13 driven off the last roller 5 and which intermeshes with the gear 14 on the stub shaft 15 associated with roller 11. Overlying the frame side members are the usual flare or deflector boards 16 downwardly inclined toward the brushes and at its elevated end the frame is provided with any suitable type of feed runway 17 overlying the gear boxes 10 for 110

directing fruit onto the highest ends of the brushes.

It will be observed that the rotation of the brushes 6 and 12 in the direction of the arrows Fig. 3 will cause a conveying and polishing of the fruit resting thereon, and that the fruit conveyed by the last brush 6 of the series against the brush 12 will, due to the elevation of the brush 12 above the plane of the brushes 6, be repelled thereby and be prevented from piling up and becoming injured by striking the edge of the flare board 16.

Having thus described my invention, what I claim as new and desire to secure by Letters Patent of the United States is:—

1. A fruit treating apparatus, comprising a bed formed of a series of parallel spaced downwardly inclined rotatably mounted brushes disposed in substantially the same plane, means for rotating the brushes in the same direction, a rotatable buffer brush arranged at one side of the series with its periphery elevated above the surface of the bed, and means for rotating said latter brush.

2. A fruit treating apparatus, comprising a bed formed of a series of parallel spaced downwardly inclined rotatably mounted brushes disposed in substantially the same plane, means for rotating the brushes in the same direction, a rotatable buffer brush arranged at one side of the series with its periphery elevated above the surface of the bed, and means for rotating all of the brushes in the same direction.

3. A fruit cleaning and polishing apparatus, comprising a bed consisting of a plurality of inclined rotatably mounted brushes disposed in parallel spaced relation with the upper surface in substantially the same plane, a buffer brush disposed at one side of the bed in a plane above the hori-

zontal plane of the brushes forming the bed, and means for rotating the brushes of the bed in a direction toward the buffer brush.

4. A fruit cleaning and polishing apparatus, comprising a bed consisting of a plurality of inclined rotatably mounted brushes disposed in parallel spaced relation with the upper surface in substantially the same plane, a buffer brush disposed at one side of the bed in a plane above the horizontal plane of the brushes forming the bed, means for rotating the brushes of the bed in a direction toward the buffer brush, and means for rotating the buffer brush.

5. A fruit cleaning and polishing apparatus, comprising a fruit supporting bed, consisting of a plurality of rotatable brushes, a buffer member disposed parallel with one side of the bed with its upper surface in a plane above the bed, means for rotating the bed forming brushes and the buffer in the same direction, and means for directing the fruit to be polished onto the bed at one end.

6. A fruit cleaning and polishing apparatus, comprising a fruit supporting bed, consisting of a plurality of rotatably mounted members disposed in substantially the same inclined plane and each provided with a spiral fruit conveying surface, means for rotating said brushes in the same direction, a rotatable brush extending parallel with one side of the bed and disposed in a plane above the cleaning and polishing brushes to provide a buffer wall longitudinally of that side of the bed toward which said bed forming brushes rotate, means for rotating said latter brush, and means for directing fruit onto the bed at one end.

In testimony whereof I have signed my name to this specification.

BRONSON C. SKINNER.
